UNITED STATES PATENT OFFICE

MAURICE M. LEVY AND WILLIAM I. SMITH, OF BROOKLYN, NEW YORK

DESIGN FOR AN EMBOSSED DISPLAY FIGURE

Application filed July 17, 1929. Serial No. 32,102. Term of patent 3½ years.

To all whom it may concern:

Be it known that we, MAURICE M. LEVY and WILLIAM I. SMITH, citizens of the United States, residing at Brooklyn, in the county of Kings and State of New York, have invented a new, original, and ornamental Design for Embossed Display Figure, of which the following is a specification, reference being had to the accompanying drawing, forming part thereof.

In said drawing:

We claim:

The ornamental design for an embossed display figure, as shown.

MAURICE M. LEVY.
WILLIAM I. SMITH.
